UNITED STATES PATENT OFFICE.

BERNARD KERN, JR., OF TOLEDO, OHIO.

CLINOMETER.

No. 809,699.

Specification of Letters Patent.

Patented Jan. 9, 1906.

Application filed January 19, 1905. Serial No. 241,746.

To all whom it may concern:

Be it known that I, BERNARD KERN, Jr., a citizen of the United States, and a resident of Toledo, in the county of Lucas and State of Ohio, have invented certain new and useful Improvements in Clinometers; and I do hereby declare the following to be a full, clear, and exact description of the invention, such as will enable others skilled in the art to which it appertains to make and use the same, reference being had to the accompanying drawings, and to the letters of reference marked thereon, which form part of this specification.

My invention relates to the class of instruments known as "clinometers;" and it consists of the several improved features of construction hereinafter specifically described.

An object of my invention is to provide an instrument of this class of improved construction whereby the spirit-glass thereof when placed to indicate any desired degree of slant will also indicate the fall in inches per foot for the degree of slant at which the glass is set, thereby saving the labor otherwise entailed upon a person using the instrument of ascertaining the fall per foot for a given degree of slant.

A further object of my invention is to provide simple and improved means for securely fastening the laterally-spaced graduated rings thereof within the opening provided therefor in the stock of the instrument, as hereinafter described.

A further object of my invention is the provision of a shoe-plate for the base of the stock that is adapted to be adjusted with respect to said stock to compensate for uneven wear on the under side thereof. This feature is very important in an instrument receiving hard usage and of which accurate calculation is required.

The invention is fully described in the following specification and shown in the accompanying drawings, in which—

Figure 1 is a top plan view of an instrument embodying my invention with a portion of the top edge plate broken away above the opening in which the spirit-glass is mounted. Fig. 2 is a side elevation thereof. Fig. 3 is a reduced top plan view of the shoe-plate of the stock, and Fig. 4 is a side view of a portion thereof.

Referring to the drawings, A represents the stock of the instrument embodying my invention. This stock is provided transversely therethrough with the circular opening B and

vertically thereof with the elongated bore or socket C, which latter is of greater length than the diameter of the opening B and of a depth suitable to enable it to intersect substantially half of the said opening, as shown by dotted lines in Fig. 2. Two rings a are mounted within the opening B and are rigidly spaced apart by a series of interposed braces or strips b, which are distributed around the peripheries thereof and secured in any suitable manner. A tongue c projects horizontally from each side of each of the rings a and is rigidly connected to the contiguous tongue of the other ring a by means of a plate d, which is soldered or otherwise secured to the lower edges of said tongues, thereby forming trough-like brackets that project within and are adapted to seat upon the adjacent portions of the bottom of the vertical bore C of the stock and act as supports for the rings a. Each of the rings a is also provided with an inwardly - extending horizontally - disposed arm e, which project in parallelism from their respective rings. A pivot e' is rotatably mounted in the free ends of the arms e in axial relation to the rings a and has the spirit-glass chair f rigidly secured thereto between the arms e and the thumb-piece e'', by which it is turned, rigidly fixed without said arms to one of its ends, as shown in Figs. 1 and 2. The chair f has its ends terminating between the rings a and each formed with an apertured lug f', in which the ends of the spirit-glass g are suitably mounted. The chair f and glass g may be turned to any desired position within the rings a by a turning of the thumb-piece e'', which is rigidly secured to the end of the pivot e', and may then be locked in adjusted position by tightening the thumb-nut h, which is threaded to one end of the pin h', said pin passing through an aperture in the arm e, against which the nut h bears, and having its opposite end rigidly fixed to the other arm. A more perfect locking of the chair f is accomplished by reason of a soft fibrous washer e''' and metal washer e'' being positioned on the pivot e' between each arm e and contiguous side of the chair f, as shown in Fig. 1. A point or finger f'' is fixed to each end of the chair f, one being adapted to register with the graduated scale i and the other with the scale i', which scales are provided on the outer surface of one of the rings a, as shown in Fig. 2. The scales i and i' are so gaged and positioned with respect to each other that when the spirit-glass g is turned so that the right-hand point

f^2 indicates on the scale i the degree of pitch sought the left-hand point f^2 will indicate on the scale i' the fall in inches per foot of an object placed at the degree of slant indicated by the other point—as, for example, should the glass be turned so that the right-hand finger f^2 points to "45" on the scale i the other finger will point to "12" on the scale i' , as shown by dotted lines in Fig. 2, thereby indicating a fall of twelve inches per foot for a slant of forty-five degrees. In addition to the above feature the spirit-glass may be positioned to determine either a plumb or level line or a greater or intermediate angle by the turning of the glass to the desired position.

An escutcheon E is suitably secured to the upper edge of the stock A in position to cover the bore or socket C therein and is provided with a central opening, through which a view may be had of the spirit-glass g , and with an opening j at each end thereof, the position of which openings is shown by dotted lines in Fig. 2.

The method employed for rigidly securing the rings a within the bore C of the stock consists in securing a cylinder or tube k in each of the end openings j in the escutcheon E , with the lower end thereof terminating a short distance above the plate d , which connects the lower edges of the contiguous tongues c of the rings a . Plaster-of-paris or other suitable cementitious substance is then poured into the tubes k and being in a semi-liquid state flows between the companion tongues c and in the crevices around the same and also fills the tubes, thereby forming a simple and very efficient method of securing the tongues c and connecting-plates d of the rings a rigidly within the bore C .

A shoe F , of metal or other suitable material, is adjustably secured to the base of the stock A by means of the screws l , which pass through the apertured countersunk portion m of said shoe and have their inner ends threaded to the sleeves or bushings n , that are mounted in the vertical bores o of the stock. A coiled expansion-spring P is mounted upon the shank of each screw between the contiguous edges of the bushing n and the countersunk portion m to effect an outward movement of the shoe when the associated screw is loosened. The shoe F is formed at each end with a lip r for engaging the lower end edges of the stock A . It will be seen that the shoe F acts both as a shield or protecting medium for the base of the stock, which is usually made of wood, and as a means for adjusting the stock to level position should it for any reason become untrue.

A plate or escutcheon G is secured to each side of the stock A and forms a marginal ring for the opening B therein.

It is obvious that such changes in the form, proportion, and minor details of construction of the parts as fairly fall within the scope of

my invention may be made without departing from the spirit or sacrificing any of the advantages thereof.

Having thus described my invention, what I claim as new, and desire to secure by Letters Patent, is—

1. In an instrument of the class described, a stock having an opening therein a pair of spaced rings mounted in said opening and having the scales i and i' thereon, a radially-disposed inwardly-projecting arm on each ring, a chair pivotally mounted between said arms and having a pointer at each end thereof adapted to register with said scales, a spirit-glass mounted in said chair, means for turning said chair, and a pin h' and nut h for causing a compression of said arms to lock the chair against movement.

2. In an instrument of the class described, a stock having a transverse opening and a socket intersecting a portion of said opening, a pair of laterally-spaced scale-rings mounted in said opening, arms radiating in parallelism from each side of said rings in position to rest upon the bottom of said bore, connection between the arms of each pair, a plate secured to the stock over said bore and having openings provided in its ends, and a tube secured to and suspended from each opening with its end terminating in juxtaposition to the pair of arms disposed thereunder for the purpose described.

3. In an instrument of the class described, a stock having a horizontal opening therein and vertically-bored portions at the sides of said opening, a frame for supporting a spirit-glass within said opening and having arms projecting from each side thereof longitudinally of said stock and seating on the bottom of said bored portions, and tubes suspended in the bored portions of said stock over the arms at each side of said frame, and a cementitious substance deposited in said tubes and upon said arms for the purpose described.

4. In an instrument of the class described, a stock having an opening therein and borings intersecting a portion of said opening, a scale-ring and spirit-glass mounted in said opening, the said ring having arms radiating from its periphery and disposed in the bored portion of the stock, and a tube suspended in the bored portion of the stock above each radiating arm for the purpose described.

5. In an instrument of the class described, a stock having a transverse opening and borings intersecting substantially half of said opening, a pair of rigidly-spaced rings mounted in said opening and each having arms radiating in parallelism from each side thereof, a plate connecting the lower edges of the parallel arms whereby a trough-like bracket is formed, and a tube suspended within the bored portion of the stock with its lower end terminating in juxtaposition to said plate whereby a cementitious substance may be deposited.

therein and flow over the plate and between the connected arms.

6. In an instrument of the class described, the combination with a stock having sockets formed in the base thereof, of a base-strip or shoe having portions countersunk within said sockets and each provided with an aperture, a screw within each countersunk portion of the base-strip and having its threaded end passed through the aperture therein and threaded

within the associated socket, and means for causing an outward movement of the base-strip when a screw is loosened.

In testimony whereof I have hereunto signed my name to this specification in the presence of two subscribing witnesses.
